ARTIFICIAL HAND

David W. Dorrance, San Jose, Calif.

Application April 16, 1935, Serial No. 16,684

1 Claim. (Cl. 3—12)

The invention relates to an artificial hand and more particularly to improvements in the subject matter of an application for United States Letters Patent filed on or about the twenty-seventh day 5 of March, 1933, and serially numbered 663,037.

The primary object of the invention is the provision of an artificial hand, wherein the elements thereof being so arranged and constructed as to enable the handling of implements or articles in 10 a practical way as these would be handled by the natural hand and without liability of the dropping of the same or the working out of position after placement thereof.

Another object of the invention is the provision of a hand of this character, wherein a cold chisel, punches or any kind of small tool required for use may be held tightly and manipulated as well as the grasping and manipulation of a table knife, fork or other article.

20 A further object of the invention is the provision of a hand of this character, which is simple in construction, thoroughly reliable and efficient in its operation, being refinements over the subject matter of an application for United States Letters Patent filed on or about the twenty-seventh of 25 March, 1933, serially numbered 663,037, strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a side elevation of the hand constructed in accordance with the invention.

Figure 2 is a plan view thereof showing by dotted lines a table knife held by the hand.

40 Figure 3 is an end elevation.

Figure 4 is a sectional view on the line 4—4 of Figure 2.

Similar reference characters indicate corresponding parts throughout the several views in 45 the drawing.

Referring to the drawing in detail, the hand includes a coupling A adapted for detachable fastening with a stump member of a conventional form. The coupling A carries as a part thereof 50 a bearing 10 constituting what might be termed a head which is formed with a stationary finger 11 the major portion thereof being relatively straight while the adjoining inner end 12 of said finger is outwardly curved to offset the same from 55 the block or head 10, which latter is cut away at

one side to provide a pivot ear 13 for the mounting therewith of the pivot end 14 of a movable finger 15 the latter for a major portion of its length being relatively straight, yet both fingers 11 and 15 are directed in a forward converging relation to each other so that the outer portions thereof approach one another. The ear 14 has fitted therewith a ball bearing equipped pivot 16 which is engaged in the head 10 so that the finger 15 will be susceptible of free movement to swing 10 relative to the stationary finger 11.

The fingers 11 and 15 carry hook-like tips 17 and 18, respectively, they being integral therewith, the said tips being cut into at their inner sides to provide interfitting shoulders 19 for assuring the firm gripping action by said tips in the use of the artificial hand. These tips 17 and 18 are curved in a meshed relation to each other and are disposed at an acute lateral angle to the fingers 11 and 15 with their free ends 20 rounded at 20 and likewise the outer surfaces 21 are suitably rounded and smooth of finish.

Formed on the fingers 11 and 15 close to the pivot 16 are external shoulders 22 for abutment therewith of an endless elastic band 23 the latter 25 encircling both fingers 11 and 15 and being relatively wide. This band 23 constitutes a tensioning medium for bringing the movable finger 15 toward the stationary finger 11 for the positive closing or bringing together of these fingers and 30 upon the opening thereof, or their separation, the band 23 will tension the same so that gripping action thereby may be had. Projected from the tips 17 and 18 at the merger thereof with the fingers 11 and 15 are outwardly extending pincer 35 jaws 24, these being at substantially right angles to the plane of the tips 17 and 18 and being provided with flat work engaging faces confronting each other, each jaw 24 having next thereto a notch 25 forming a seat for an implement or an 40 artificer's tool or a knife or the like.

The movable finger 15 is actuated and controlled by a trigger 26 having an eye 27 for the attachment thereto of a pull cord and this trigger is offset from the inner end of the finger 15 and provides a shoulder as at 28 for the elastic band 23 while the finger 11 at the end 12 has an offset 29 which likewise forms an abutment for the said band so as to prevent riding of the band in the operation of the hand. The pull cord is not shown 50 and is operated as usual from the shoulder portion of a person wearing the hand.

The fingers 11 and 15 in close proximity to the shoulders 22 have formed therewith opposite confronting forks 30 directed toward each other, 55

while the fingers 11 and 15 at the said shoulders 22 are provided with the squared companion notches or recesses 31 which afford a seat for an article, as for example the handle 32 of a knife 33, the blade of the latter being clamped between the jaws 24 and latched by a hook 34 at its bill 35. This hook 34 extends laterally to one side of one jaw 24 at the innermost portions thereof.

5 The jaws 24, forks 30, recesses or notches 31 and the hook 34 constitute the improvements over the 10 subject matter of the application for United States Letters Patent filed on or about the twenty-seventh day of March, 1933, serially numbered 663,037.

15 In the use of the hand, heavy loads may be carried thereby and various tools clamped and manipulated when engaged by the hand, as for example a cold chisel, punches or any kind of small tool may be firmly and tightly held or a 20 butcher or table knife and in fact any kind of knife or other implement.

What is claimed is:

In an artificial hand of the kind described, relatively movable fingers, curved tips on said fingers and disposed at an acute angle thereto, shoulders formed on the inner faces of the tips and interfitting with each other, pincer jaws extended from the fingers at right angles thereto at the point of merger of said fingers and tips, a hook extending from one of the pincer jaws and lying in the plane thereof and projected at right angles thereto, a ball bearing equipped pivot connecting the fingers for swinging movement relative to each other, shoulders formed on the fingers close to the said pivot, tensioning means encircling the fingers and abutting the said shoulders, the fingers at the shoulders being provided with opposed confronting seating notches, and forks on said fingers in opposite relation to each other next to the shoulders.

20 DAVID W. DORRANCE.
